UNITED STATES PATENT OFFICE.

WILLIAM H. OSBORN, OF SOUTHERN HEIGHTS, KENTUCKY.

AUTOMATIC FLUSHING APPARATUS FOR WATER-CLOSETS.

No. 914,068.

Specification of Letters Patent.

Patented March 2, 1909.

Application filed February 5, 1906. Serial No. 299,507.

To all whom it may concern:

Be it known that I, WILLIAM H. OSBORN, a citizen of the United States, residing at Southern Heights, in the county of Jefferson 5 and State of Kentucky, have invented a new and useful Automatic Flushing Apparatus for Water-Closets, of which the following is a specification.

This invention relates to apparatus for 10 flushing water closets; and the objects of my improvement are, to provide a water closet which will flush automatically, of which the working parts are inclosed so as to be safe from tampering and accidental de- 15 rangement and hidden from view so as to avoid an unsightly and complicated appearance, simplicity of construction, facility of operation, and ease and comparative inexpensiveness of manufacture.

20 These objects I attain by means of the mechanism illustrated in the accompanying drawings, in which—

Figure 1 is a vertical sectional view; Fig. 2, a side elevation with the near end of the tank 25 removed; and, Fig. 3, a plan view with the tank removed.

Similar reference numerals refer to similar parts throughout the several views of the drawings.

30 The stop-valve 1, the flush-valve 7, and the seat extension or lever 5 constitute the body of the invention. The tank 2 is of the ordinary low-tank type, and the flush-valve 7 is of the conventional hollow float type having 35 a stem, 8, extending upward. Stem 8 passes through a guide, 9. Stem 10 extends from valve 7 downward into tail-piece 31 of valve-seat 32 and through guide 11. Immediately under valve 7 and in its axis is the stop-valve, 40 1, for the purpose of holding the water in tank 2 when flush-valve 7 has been unseated. Stop-valve 1 has a tubular upper portion 35, provided with a collar and a union nut 33 by means of which it is attached to part 31.

45 The body of stop-valve 1 is somewhat enlarged to accommodate the valve mechanism. In the upper tubular portion 35 is a guide, 12, for guiding stem 10 and also for abutment of a coil spring, 20. The valve- 50 seat 30 is formed on the body of the valve at the lower end of the tubular portion 35. The valve-disk 22 is provided with upward extending guide stems, 27, adapted to bear

against the inner surface of portion 35 and preserve the central alinement of the disk. 55 Disk 22 is also provided with two integral stems, 21 and 26, extending upward and downward respectively from the disk. Over stem 21 is placed the coiled compression spring 20 so arranged as to press the disk 60 normally downward. The disk is provided with a gasket, 23, preferably made of rubber, for seating against valve-seat 30. Stem 26 has a downward extension, 13, which is bored with an axial hole to accommodate 65 stem 26. A washer or gasket, 36, is placed over stem 26 between the disk and the upper end of part 13. The lower end of stop-valve 1 is closed by a plug, 24, which is sufficiently large so that disk 22 may be inserted through 70 the opening. Plug 24 is sealed with a gasket, 25. It is provided with an integral upward extending tubular portion into which stem 13 fits snugly and in which it slides on the top of which disk 22 normally 75 rests. Plug 24 is provided on the outside with a central stuffing-box, 28, to prevent leakage about stem 13. The body of stop-valve 1 is provided with a union for attachment to the closet bowl. Stem 13 is provided at its lower end with a friction roller, 14, and side plates or guides 29.

The closet seat 4 is hinged to the bowl in the usual manner, is preferably cast of metal and hollow underneath, and is provided with 85 a lug, 19, on its under surface. On the same hinge with seat 4 is pivoted a valve-operating lever, 5 by means of hinge-pin 16, which extends under the rear end of seat 4, then backward from the hinge, encircling the 90 flush pipe, and terminating in a flattened extension. The seat extension 5 may be made integral with the seat casting 4. This extension is bored vertically at its rear end and threaded and carries a wear-plate, 15, 95 which is vertically adjustable and adapted to work against friction roller 14. The guides 29 extend downward on either side of the rear extension of lever 5 and wear-plate 15 and keeps these parts in operative alinement with friction roller 14. The forward end of lever 5 which extends under seat 4 is provided with a boss, 17, pierced and threaded to receive an adjusting screw, 18. Adjusting screw 18 is used to adjust the angle 100 of seat 4 relative to the closet bowl and lever 105

5 so that when the seat is pressed down on the bowl, lever 5 will press disk 22 of the stop-valve firmly against valve-seat 30 and yet not cause an excessive strain on lever 5 and the other working parts.

The operation of the apparatus will now be understood. The tank 2 fills with water in the ordinary way, the water being held in the tank by valve 7. Valve 1 is normally open, stem 13 and disk 22 being depressed by spring 20, lever 5 is depressed and seat 4 is elevated at the front end. When seat 4 is depressed at the front end by the occupant, the rear end of lever 5 is elevated, stem 13 is pushed up until it carries disk 22 upward and presses it firmly against seat 30. Stem 21 comes in contact with stem 10 of float-valve 7 and raises it off its seat so that it rises and floats in the water. The water now descends through the opening in the valve-seat 32 but is stopped and prevented from flushing the closet by disk 22. When seat 4 is released by the occupant rising, the front end is raised by the rear end being depressed by stem 13, disk 22 drops, and the water flows from tank 2 through flush pipe 6 and flushes the closet. Valve 7 reseats itself as soon as the tank is empty, and the tank is refilled in the ordinary way ready for the flushing operation to be repeated.

Having thus described my invention so that any one skilled in the art pertaining thereto may make and operate it, I claim—

1. In flushing apparatus for water closets, 35 in combination, a tank normally filled with water, a valve-seat in the bottom of said tank, a float-valve for said valve-seat to hold the water normally in said tank, a closet-bowl, a stop-valve detachably secured to the 40 tail-piece of said valve-seat and to said bowl and comprising a hollow body, a valve-seat and a valve-disk, a hinged seat on said closet-bowl, a lever on said seat operatively connected with said stop-valve and said stop-valve operatively connected with said float-valve, all said parts so coöperating that when said seat is depressed said seat lever raises and closes said stop-valve and said stop-valve in turn raises and unseats and 50 opens said float-valve, substantially as specified.

2. In apparatus for flushing water closets, the combination of an open tank, a float-valve, said float-valve provided with an upper 55 per and a lower stem, a guide for the upper stem and a guide for the lower stem of said float-valve, a stop-valve interposed between said tank and the closet bowl, an upper stem on said stop-valve and a lower stem on said 60 stop-valve, a spring to hold said stop-valve normally from its seat, said upper stem of stop-valve adapted to work against said lower stem of said float-valve and raise said float-valve from its seat, a friction-roller on

the lower end of the lower stem of said stop-valve, a pivoted lever, an adjustable wear-plate on one end of said pivoted lever adapted to work against said friction-roller, a hinged seat, and means for adjusting said lever in relation to said hinged seat, so that 65 when said hinged seat is depressed said stop-valve is closed and said float-valve is opened and when said hinged seat is released said stop-valve is opened and the closet flushed, substantially as specified.

3. In water closet flushing apparatus, in combination, a bowl, a tank normally filled with water, a flush-valve in the bottom of said tank for holding the water normally in said tank, and a stop-valve attached under 70 said flush-valve which is normally open for preventing the flush water flowing out on unseating said flush-valve, said stop-valve comprising a body separable from said tank and said bowl, a valve-seat, a valve-disk, a stem on each side of said valve-disk, and one of said stems protruding through the wall of said body, and a spring within said body to press said disk normally to the open position, 75 substantially as specified.

4. In flushing apparatus for water closets, the combination of a bowl, an open low tank normally filled with water, a valve-seat in the bottom of said tank having a depending neck, a flush-valve in said tank having a depending stem placed within said neck, a stop-valve between said flush-valve and said bowl, a stem protruding from the bottom of said stop-valve, and a seat actuated lever adapted to lift said stem, substantially as 90 specified.

5. Apparatus for flushing water closets, comprising in combination an open low tank normally filled with water, a flush-valve normally closed, a stop-valve coöperating with 95 said flush-valve to hold the water in said tank after said flush-valve has been opened, and an adjustable extension of the seat in operative contact with the stem of said stop-valve for lifting said stop-valve and said flush-valve, substantially as described.

6. In water closet flushing apparatus, the combination of a tank normally filled with water, a flush-valve, a stop-valve coöperating with said flush-valve to unseat it and hold 115 the water in said tank till released, a stem protruding axially downward from said stop-valve, a pivoted lever attached to the closet seat operatively connecting the stem of said stop-valve with the closet seat in such a manner that when the closet seat is depressed said flush-valve is lifted and opened and said stop-valve is lifted and closed and constituting automatic valve-actuating means, and means for adjusting the amplitude of motion of said 120 pivoted lever between itself and the closet seat, substantially as described.

7. In flushing apparatus for water closets,

the combination of a tank normally filled with water, a flush-valve provided with a downward-extending stem, a stop-valve provided with an upward-extending stem working against said downward-extending stem, a protruding downward extending stem from said stop-valve, and a lever operatively

connecting said stop-valve and said flush-valve with the seat of the closet, substantially as specified.
